Attorney

UNITED STATES PATENT OFFICE.

GEORGE SHARPE WHITE, OF NASHVILLE, TENNESSEE.

BURIAL-CASKET.

1,289,990.

Specification of Letters Patent. Patented Dec. 31, 1918.

Application filed August 3, 1918. Serial No. 248,141.

To all whom it may concern:

Be it known that I, GEORGE S. WHITE, a citizen of the United States, residing at Nashville, in the county of Davidson and State of Tennessee, have invented new and useful Improvements in Burial-Caskets, of which the following is a specification.

This invention relates to burial caskets, and has for its object the provision of a casket having its entire cover formed of transparent material whereby a full view may be had of the body within the casket, the cover being formed of sections hingedly connected with the body portion of the device and arranged in overlapping relation, both sections being provided with side flanges and the flanges of one section being adapted for straddling engagement with the flanges of the other section.

An important object is the provision of a casket of this character in which the cover sections are provided with retaining members upon which ornamental draperies may be hung and upon which wreaths or other floral pieces may be suitably supported, one of these retaining members further serving as a handle whereby the uppermost covered section may be raised and lowered, and the endmost retaining members serving as stops to limit the swinging of the cover sections.

Another object is the provision of a casket of this character which will be extremely ornamental in appearance, comparatively simple and inexpensive in manufacture, efficient in service and a general improvement of the art.

With the above and other objects and advantages in view the invention consists in the details of construction to be hereinafter more fully described and claimed, and illustrated in the accompanying drawing, in which:—

Figure 1 is a perspective view of the casket.

Fig. 2 is a longitudinal sectional view showing the cover closed in full lines and open, in dotted lines.

Fig. 3 is a cross sectional view.

Referring more particularly to the drawing the numeral 5 designates the body portion of the device which includes a bottom wall 6, side walls 7 and end walls 8. In the practical carrying out of my invention, this body portion may be formed of any suitable material though I preferably construct it of celluloid which may be either transparent

or opaque, as desired. It will be noted that one end wall 8 is higher than the other end wall whereby the top of the body portion will be inclined as shown. Suitable handles 9 are secured at any desired location upon the side or end walls and the exterior as well as the interior of this body portion may be suitably ornamented. In the event that this body portion is formed of opaque material, it is preferable that the interior be lined with suitable ornamental fabrics whereby to present a very pleasing appearance.

The top of this body portion 5 which forms the receptacle in which the corpse is disposed, is closed by two suitable cover sections 10 and 11 which are pivotally connected with the side 7 adjacent the end walls 8 as shown at 12 and 13. The cover section 10 is of less length than the length of the body portion 5 so as to extend only partly of the length thereof and is provided at its sides with flanges 14 adapted to snugly embrace outer surfaces of the side walls 7. The section 11 is the same in construction as the section 10 and is adapted to engage over the section 10 with its flanges 15 disposed outwardly of the flanges 14 on the section 10. The sections 10 and 11 are each longer than one half the length of the body portion 5 whereby they will be arranged in overlapping relation when closed.

In order to provide means whereby drapery of any suitable kind or whereby floral pieces may be suspended from the casket, I provide retaining members 16 and 17 formed on the pivoted ends of the sections 10 and 11 and preferably angular shaped as shown whereby the drapery or floral decorations may be readily engaged thereon. These retaining members also serve as stops to limit outward swinging of the cover sections.

At the free end of the cover section 11, I provide an upwardly extending member 18 which is angularly shaped as shown and which extends toward the retaining member 17. This member 18 is preferably formed from the material of the cover section 11 by splitting the cover section 11 inwardly from its free end and bending the resultant tongue of material upwardly. This member 18 not only serves as a means for supporting drapery or floral pieces but also serves as a handle whereby the cover section 11 may be raised and lowered.

While I have shown and described my in-

vention as reduced to a simple form, it will of course be readily understood that the entire device may be made as ornamental as desired and that various alterations in the shapes, sizes and proportions of the parts may be resorted to and still be within the spirit of the invention. The construction of the device from celluloid, while not absolutely essential, is preferred for the reason that celluloid is an extremely light material and possesses the further advantage of being transparent whereby a full view of the corpse within the casket may be obtained at all times.

Having thus described my invention I claim:

1. A burial casket comprising a rectangular open topped body forming a receptacle, a pair of cover sections pivotally connected 20 with the sides of said body portion adjacent the ends thereof and arranged in overlapping relation, flanges formed on the longitudinal edges of said cover sections, the flanges on one section being disposed outwardly of the flanges on the other section when said sections are overlapped, upwardly extending angular retaining members formed on the pivoted ends of said

cover sections and engageable with the adjacent end wall of the body for holding said cover sections in upwardly inclined divergent relation when said covers are swung to open position, and a similar retaining member formed on the free edge of the overlapping section, all of said retaining members serving as supports for holding drapery and floral decorations.

2. A burial casket comprising an open topped body having one end of greater height than the other end whereby the top will be inclined, a pair of cover sections pivotally connected with the sides of said body adjacent the ends thereof and arranged in overlapping relation, flanges formed on the longitudinal edges of said cover sections, 45 upwardly extending retaining members formed from the material of said sections adjacent the pivoted ends thereof and engageable with the end walls of said body for holding said cover sections in elevated 50 position when open, said retaining members being angular in cross section whereby to serve as supports for decorations.

In testimony whereof I affix my signature.

GEORGE SHARPE WHITE.
